UNITED STATES PATENT OFFICE.

EDGAR LOUIS STREAM AND WILLIAM J. GIBBENS, OF NEW ORLEANS,
LOUISIANA.

OIL-BURNER.

No. 857,496.

Specification of Letters Patent.

Patented June 18, 1907.

Application filed September 20, 1906. Serial No. 335,457.

To all whom it may concern:

Be it known that we, EDGAR LOUIS STREAM and WILLIAM J. GIBBENS, citizens of the United States, residing at New Orleans, in the parish of Orleans and State of Louisiana, have invented certain new and useful Improvements in Oil-Burners; and we do hereby declare the following to be a full, clear, and exact description of the invention, such as will enable others skilled in the art to which it appertains to make and use the same.

Our invention relates to improvements in oil burners of that type in which the oil is atomized and is blown into the furnace by the *vis viva* of one or more jets of steam.

Our invention will be understood by reference to the accompanying drawing, which shows the burner in central vertical section with the steam pipes in elevation.

A represents a casting containing a mixing chamber and provided with the curved enlarged rear end A' and the tapered passage A² and the bottom outlet passage A³. This casting is provided with screw threads a', a² and a³.

B represents a curved pipe opening into said mixing chamber forward of said enlarged portion A' provided with a flange b⁴ held beneath the shoulder a⁴ of the casting and provided with the conical inlet b' and the curved outlet b².

C represents a sleeve, flanged as at c and held by the shoulder d of the cap D which is screwed over the screw thread a³. This sleeve C is screw-threaded as at c' to engage the screw threads e' of the oil pipe E. Between this pipe and the sleeve C is an annular chamber C⁶ above which is a flange E⁶ secured to the pipe E and slotted as at e⁶. The upper end of the pipe E terminates in the nozzle e² which is spaced from the coned inlet b' of the curved pipe B, thus leaving a tapered annular passage between the two.

F represents the steam pipe which is provided with two branches F' and F² controlled by the valves G and G' respectively. The branch F' opens into the annular chamber C⁶ and the branch F² is screwed into the socket h of the plug H, which plug engages

the screw-threads a' and thus closes the rear or large end of the casting A. This plug H is preferably provided with a curved tapered end H', and with a chamber H⁰ connected to the branch pipe F², and connected with the mixing chamber by the perforations h⁰.

K represents a cap generally similar to the cap D, to which any suitable nozzle or twyer may be connected.

The operation of the device is as follows:— Suppose it is only desired to feed a limited supply of oil to the furnace, the pipe E being connected to the source of oil supply in the usual well known way, and controlled by any suitable valve, not shown, oil is forced by pump or gravity through nozzle e², and steam is admitted through the pipe F'. This steam will rush through the openings e⁰, forcing up the oil through the nozzle e², and the mixture will pass through the outlet b² and striking the curved tapered plug H', the oil will be thoroughly atomized and will be blown backward through the outlet A² to the furnace. In this operation the branch pipe F² and the chamber H⁰ and perforations h⁰ have no function; but if it is desired to still further increase the supply of atomized oil fed to the furnace, open wider the feed valve (not shown) in the supply pipe E, turn on steam also through the pipe F². This second supply of steam will enter the chamber H⁰, and rushing forward through the perforations h⁰, will cause a larger supply of oil to be atomized and therefore more oil can be supplied through the pipe E, and this will become thoroughly atomized by the currents of steam meeting each other at varying angles, and the entire mass will be blown through the passage A² to the furnace.

We do not mean to confine the invention to the precise details of construction or to the precise combinations and arrangements of parts, as these may be varied in many respects without departing from the spirit of our invention.

Having thus described our invention, what we claim and desire to secure by Letters Patent of the United States is:—

1. In an oil burner, the combination with a mixing chamber provided with an enlarged

mixing portion and a tapered delivery portion, of a curved conical plug closing the enlarged end of the chamber, a curved pipe having its outlet in front of said plug and provided with a conical base, an oil pipe provided with a conical nozzle opening into said base and spaced therefrom, a slotted flange surrounding said oil pipe at the base of said nozzle, and means for forcing steam under pressure through said slotted flange, substantially as described.

2. In an oil burner, the combination with a mixing chamber provided with an enlarged mixing portion and a tapered delivery portion, of a curved conical plug closing the enlarged end of the chamber, a curved pipe having its outlet in front of said plug and provided with a conical base, an oil pipe provided with a conical nozzle opening into said base and spaced therefrom, a sleeve engaging said oil pipe and spaced therefrom to form an annular chamber, a slotted flange or ring partly closing said annular chamber at the base of said nozzle, and means for forcing steam under pressure into said annular chamber, substantially as described.

3. In an oil burner, the combination with a mixing chamber provided with an enlarged mixing portion and a tapered delivery portion, of a curved perforated conical plug closing the enlarged end of the chamber, means for blowing steam through the perforations in said conical body, a curved pipe having its outlet in front of said plug and provided with a conical base, an oil pipe provided with a conical nozzle opening into said base and spaced therefrom, a slotted flange surrounding said oil pipe at the base of said nozzle, and means for forcing steam under pressure through said slotted flange, substantially as described.

4. In an oil burner, the combination with a mixing chamber provided with an enlarged mixing portion and a tapered delivery portion, of a curved perforated conical plug closing the enlarged end of the chamber, means for blowing steam through the perforations in said conical body, a curved pipe having its outlet in front of said plug and provided with a conical base, an oil pipe provided with a conical nozzle opening into said base and spaced therefrom, a sleeve engaging said oil pipe and spaced therefrom to form an annular chamber, a slotted flange or ring partly closing said annular chamber at the base of said nozzle, and means for forcing steam under pressure into said annular chamber, substantially as described.

5. In an oil burner, the combination with a mixing chamber provided with an enlarged mixing portion and a tapered delivery portion, of a curved conical plug closing the

larged end of the chamber, the said plug being provided with perforations grouped around its axis, means for forcing steam through said perforations, a curved pipe having its outlet in front of said plug and provided with a conical base, an oil pipe provided with a conical nozzle opening into said base and spaced therefrom, a slotted flange surrounding said oil pipe at the base of said nozzle, and means for forcing steam under pressure through said slotted flange, substantially as described.

6. In an oil burner, the combination with a mixing chamber provided with an enlarged mixing portion and a tapered delivery portion, of a curved conical plug closing the enlarged end of the chamber, the said plug being provided with perforations, a curved pipe having its outlet in front of said plug and provided with a conical base, an oil pipe provided with a conical nozzle opening into said base and spaced therefrom, a sleeve engaging said oil pipe and spaced therefrom to form an annular chamber, a slotted flange or ring partly closing said annular chamber at the base of said nozzle, and a steam pipe having two separately controlled branches for forcing steam under pressure into said annular chamber and also through said perforations in said plug when desired, substantially as described.

7. In an oil burner, the combination with a mixing chamber provided with an enlarged mixing portion and a tapered delivery portion, of a curved conical plug closing the enlarged end of the chamber and provided with an internal chamber, and perforations opening therefrom into the mixing chamber, a curved pipe having its outlet in front of said plug and provided with a conical base, an oil pipe provided with a conical nozzle opening into said base and spaced therefrom, a slotted flange surrounding said oil pipe at the base of said nozzle, and a steam pipe having two separately controlled branches for forcing steam under pressure through said slotted flange and also through said perforations in said plug when desired, substantially as described.

8. In an oil burner, the combination with a mixing chamber provided with an enlarged portion and a tapered delivery portion, of a curved conical plug closing the enlarged end of the chamber and provided with an internal chamber, and perforations opening therefrom into the mixing chamber, a curved pipe having its outlet in front of said plug and provided with a conical base, an oil pipe provided with a conical nozzle opening into said base and spaced therefrom, a sleeve engaging said oil pipe and spaced therefrom to form an annular chamber, a slotted flange or

ring partly closing said annular chamber at the base of said nozzle, and a steam pipe having two separately controlled branches for forcing steam under pressure into said annular chamber and also through said perforations in said plug when desired, substantially as described.

In testimony whereof, we affix our signatures, in presence of two witnesses.

EDGAR LOUIS STREAM.

WILLIAM J. GIBBENS.
